UNITED STATES PATENT OFFICE.

ABRAHAM J. LOBAR, OF NEW YORK, N. Y.

SEPARABLE BUTTON.

1,302,390.

Specification of Letters Patent. Patented Apr. 29, 1919.

Application filed November 5, 1918. Serial No. 281,292.

To all whom it may concern:

Be it known that I, ABRAHAM J. LOBAR, a citizen of the United States, and a resident of the city of New York, borough of the Bronx, in the county of Bronx and State of New York, have invented a new and Improved Separable Button, of which the following is a full, clear, and exact description.

The invention relates to buttons such as are used mainly on garments and other wearing apparel, and its object is to provide a new and improved separable button arranged to permit the manufacturer or user to conveniently fasten the button members together and in position on the cloth, leather, rubber or other material of the article on which the button is used, or to disconnect the said members for removal of the button from the article for reuse at the same or any other place. Another object is to permit the use of an ordinary pointed shank as one of the members of the separable button thereby reducing the cost of producing the button and dispensing with expensive machinery and highly skilled labor in the manufacture of the button. Another object is to provide a separable button which is very simple and durable in construction and not liable accidentally to become detached from the garment or other article on which it is used.

With these and other objects in view, the invention consists of certain novel features of construction as hereinafter shown and described and then specifically pointed out in the claims.

A practical embodiment of the invention is represented in the accompanying drawings forming a part of this specification, in which similar characters of reference indicate corresponding parts in all the views.

Figure 1 is an enlarged sectional plan view of the separable button in position on an article;

Fig. 2 is a rear face view of the head of the button;

Fig. 3 is a plan view of the shank and its holding member;

Fig. 4 is a plan view of the coöperating member adapted to be engaged by the shank; 50 and

Fig. 5 is a perspective view of the disk

provided with gripping jaws adapted to engage the shank.

The improved separable button comprises in its general construction a head 10 carrying a shank 11 adapted to engage a coöperating receiving member 12 after the shank 11 has been forced through the cloth, leather, rubber or other material 13 of the garment or other article on which the button is used. The head 10 is preferably made of a plastic material adapted to set and harden in a suitable mold which gives it the desired shape, and in the back or under side of the button is embedded a cup-shaped member 15 provided with an annular crimped flange 16 embedded in the plastic material of the head while the latter is formed in the mold so that the cup-shaped member 15 is firmly held in position in the head with the bottom 17 of the cup-shaped member 15 centrally at the under side of the head. The bottom 17 is provided with a central struck-up portion 18 extending outwardly and adapted to be seated on one face of the material 13, as plainly shown in Fig. 1. The struck-up portion 18 has an inwardly extending annular gripping jaw 19 into which extends the base end 20 of the shank 11 to securely fasten the said shank to the cup-shaped body 15. The bottom 17 of the cup-shaped member 15 is further provided at diametrically opposite points with struck-up lugs 21 bent inwardly and toward each other to form an abutment for the end of the base 20 of the shank 11 to prevent the latter from being accidentally pushed inward when forcing the shank 11 through the material 13. The cup-shaped member 15 is adapted to be closed by a cover 22 preferably made cup shape and snugly fitted with its mouth into the cup-shaped member 15, as plainly indicated in Fig. 1. The portion of the cover 22 projecting outward from the cup-shaped member 15 is embedded in the plastic material of the head 10 and aids the cup-shaped member 15 to hold the latter securely in position in the plastic material of the head 10.

The coöperating or engaging member 12 is formed of a cup-shaped body 25 provided at its bottom 26 with a central opening 27 for the passage of the pointed end 28 of the

shank 11. In the body 25 and resting on the bottom 26 is a disk 30 provided with struck-up jaws 31 bent outwardly, as plainly shown in Fig. 1, and gripping the shank 11 adjacent the pointed end thereof. The edge of the disk 30 is held in an annular groove 32 formed in the body 25 adjacent the bottom 26 thereof. A closing plate 35 serves to close the mouth of the body 25 and its edge is held in an annular groove 36 formed in the outer end of the body 25. It will be noticed that this closing plate 35 limits the movement of the shank 11 into the member 12.

In using the separable button, the head 10 and its shank 11 are detached from the co-operating member 12 to permit the user to force the shank 11 through the material 13 of the article on which the button is used. The co-operating member 12 is now forced into the pointed end of the shank by engaging the point 28 with the central aperture 27 and finally forcing the pointed end up between the jaws 31 which are then bent outwardly and firmly grip the shank at opposite sides thereof. It will be noticed that the bottom 26 of the co-operating member 12 is seated against the inner face of the material 13 thus holding the button securely in position on the material and with the under side of the head 10 slightly spaced from the outer face of the material to permit convenient buttoning of the head of the button with the buttonhole in the part to be fastened to the part carrying the button.

It is understood that the disk 30 is preferably made of steel to provide securely gripping jaws 31 which firmly impinge the sides of the shank 11 to hold the co-operating member 12 firmly in position on the shank 11 and thereby fasten the button securely in place on the material 13. In case it is desired to remove the button from the material 13 it will be necessary for the user to take hold of the head 10 with one hand and of the member 12 with the other hand and then forcibly turn the member 12 on the shank 11 and exert a strong pull on the said member to gradually disengage the jaws 31 from the shank 11. The button can then be reused if desired. It will be noticed that by the arrangement described an ordinary shank 11 is used thereby reducing the cost of producing the button to a minimum. It will also be noticed that the holding member 55 of the shank 11 is securely fastened in place in a plastic material forming the ornamental head of the button, and the shank is securely fastened in such holding member to prevent the parts of the head from accidentally coming apart.

Having thus described my invention, I claim as new and desire to secure by Letters Patent:—

1. A separable button, comprising a head, a plain shank having at one end a base and having the other end pointed, a gripping member carried by the head for gripping the base of the shank to hold it in the head, and a co-operating member made hollow and having an entrance for the pointed end of the said shank, the said co-operating member being provided with interior gripping means gripping the entering end of the shank. 65

2. In a button, a head of plastic material, a shank holding member having a flange 75 embedded in the said head, the said member being provided with central retaining means, and a shank having a base and a pointed end, the said base being held in the said retaining means. 80

3. In a button, a head of plastic material, a shank holding member having a flange embedded in the said head, the said member being provided with central retaining means and a shank having a base and a pointed 85 end, the said base being held in the said retaining means, and a cup-shaped covering member fitting over the said shank holding member and embedded in the said head.

4. In a button, a head of plastic material, 90 a shank-holding member on the under side of the said head and having a cup-shaped body provided with a crimped flange embedded in the said head, the said holding member having a central portion projecting 95 outward from the under side of the said head, the said central portion having struck-up gripping jaws extending inwardly, and a plain shank having its base end extending into the central portion and gripped by the 100 said jaws.

5. In a button, a head of plastic material, a shank-holding member on the under side of the said head and having a cup-shaped body provided with a crimped flange 105 embedded in the said head, the said holding member having a central portion projecting outward from the under side of the said head, the said central portion having struck-up gripping jaws extending inwardly and 110 the said central portion having a struck-up abutment spaced inwardly from the said jaws, and a plain shank having a base entering the said central portion and gripped by the said jaws, the end of the base abutting 115 against the said abutment.

6. In a button, a shank having a head at one end and a point at the other end, a co-operating engaging member adapted to engage the pointed end of the said shank, the 120 said engaging member having a cup-shaped body provided in its bottom with a central entering aperture for the passage of the said shank, a flat disk held in the said body adjacent the bottom thereof, the disk having 125 gripping jaws gripping the said shank, said

jaws being struck-up from the central portion of the disk, and a closing plate closing the open end of the body, the said body being provided with annular grooves of which 5 one is engaged by the edge of the said disk and the other by the edge of the said plate.

7. In a button a head, a shank having a base end and having its other end pointed,

a member secured to the head and having downwardly and inwardly extending gripping members for engaging the base of the shank and upwardly and inwardly extending members forming an abutment for the base of the shank. 10
